Primary Examiner — Leanne Was-Englehart*(74) Attorney, Agent, or Firm* — Maier & Maier, PLLC(57) **CLAIM**

The ornamental design for a drill bit accessory, as shown and described.

DESCRIPTION

FIG. 1 is a perspective view of a drill bit accessory, showing my design;

FIG. 2 is a top view thereof;

FIG. 3 is a bottom view thereof;

FIG. 4 is a right side view thereof;

FIG. 5 is a left side view thereof;

FIG. 6 is a rear side view thereof; and,

FIG. 7 is a front side view thereof.

The broken lines depict portions of the drill bit accessory that form no part of the claimed design.

1 Claim, 5 Drawing Sheets(56)
